UNITED STATES PATENT OFFICE

NATHAN ERNEST RICKEY, OF MASSILLON, OHIO

COMBINED HOSE SUPPORTER AND HOSE

Application filed January 20, 1932. Serial No. 587,781.

This invention relates to a combined hose supporter and hose.

An object of the invention is the construction of a hose, which is provided with a supporter of a very simple construction and which will automatically adjust itself to the leg of the wearer, thereby efficiently supporting the hose in position.

Another object of the invention is the construction of a hose supporter as a part of the hose, said hose supporter being of such novel construction as to form a leg-encircling loop, which is freely adjustable to any size leg for efficiently supporting the hose in position upon the leg.

With the foregoing and other objects in view, my invention comprises certain novel constructions, combinations and arrangements of parts as will be hereinafter fully described, illustrated in the accompanying drawing, and more particularly pointed out in the appended claim.

In the drawing:

Figure 1 is a fragmentary perspective view of the device, showing the same as when applied to a leg.

Figure 2 is a fragmentary, perspective view of the device, prior to the long strap being threaded through its slot for forming the freely slideable and automatically adjustable leg-encircling loop.

Figure 3 is a diagram showing the method of threading the strap through the slot for forming the loop shown in Fig. 1.

Referring to the drawing by numerals, 1 designates the body of the hose, which may be any kind of a stocking, sock or the like. In the embodiment shown in the drawing, I have preferably illustrated the strap 2 as being an integral part of the body 1 by knitting or weaving the strap at the time the body is constructed. However, the strap 2 may be attached to the body 1 in any suitable manner.

I employ only a single strap 2, of sufficient

length to entirely encircle the wearer's leg. This strap is provided with a single long slot 3 at its outer end, which slot preferably extends longitudinally of the strap; this slot 3 is longer than the width of the strap, for the purpose as hereinafter described:

To form the automatically adjustable loop (Fig. 1), the strap 2 is threaded through slot 3 in a doubled or folded condition as illustrated by "A" in Fig. 3, until the complete loop is formed as shown in Fig. 1. I have found from actual experience that the strap will assume the position shown in Figure 1, by the operator pulling on the "loop" "A" (Fig. 3), until all of the loose outer portion has been threaded through the slot 3, whereupon the slotted end will turn "inside out", so to speak, actually assuming the exact position shown in Fig. 1.

I am aware that a number of patents have been issued upon hose supporters, involving straps attached to the hose of different kinds, but the art does not show my simple and efficient invention involving only a single long strap with a single slot at its outer end.

Many advantages may be ascribed for my novel structure, among which can be mentioned the fact that the more the hose sags, the tighter the loop grips or binds upon the leg to hold the stocking or sock from wrinkling. Further, the peculiarly formed loop permits free adjustment to any size leg. The action of the loop, sliding freely in the slot, is therefore, automatic.

While I have described the preferred embodiment of my invention and illustrated the same in the accompanying drawing, certain minor changes or alterations may appear to one skilled in the art to which this invention relates, during the extensive manufacture of the same, and I, therefore, reserve the right to make such changes or alterations as shall fairly fall within the scope of the appended claim.

What I claim is:

As a new article of manufacture, a single-piece hose body and strap, said strap provided at its outer end with a long slot of a length greater than the width of the strap, and portions of said strap between its ends laid full-width together and threaded freely through said long slot forming an automatically adjustable loop to grip a leg, substantially as shown and described.

In testimony whereof I hereunto affix my signature.

NATHAN ERNEST RICKEY.
